UNITED STATES PATENT OFFICE.

JOHN M. GOODWIN, OF SAN FRANCISCO, CALIFORNIA.

FIREPLACE DAMPER.

1,413,472.

Specification of Letters Patent. Patented Apr. 18, 1922.

Application filed October 18, 1920. Serial No. 417,563.

To all whom it may concern:

Be it known that I, JOHN M. GOODWIN, a citizen of the United States, residing at San Francisco, in the county of San Francisco and State of California, have invented new and useful Improvements in Fireplace Dampers, of which the following is a specification.

This invention relates to improvements in fire place dampers and has particular reference to an apparatus for the control of drafts in open fire places.

One object of this invention is to provide a damper for an open fire place which may be operated from the front outside of the chimney hearth to adjust the apparatus to various positions and retain the same in such positions when adjusted.

Another object of this invention is to provide a damper of the character described which is simple in construction, economical in manufacture, and in which the parts are so designed and arranged that they can be readily put into operative condition and placed in the fire place by unskilled labor.

Other objects and advantages of the invention will be apparent during the course of the following description.

In the accompanying drawing forming a part of this application and in which like numerals are employed to designate like parts throughout the same,

Figure 1 is a front elevation of an open fire place showing the apparatus in position, Figure 2 is a vertical sectional view taken on the line 2—2 of Figure 3,

Figure 3 is a horizontal sectional view taken on the line 3—3 of Figure 1, and

Figure 4 is a view in detail showing a fastening forming part of my invention.

In the drawing wherein for the purpose of illustration is shown a preferred embodiment of my invention, the numeral 5 represents a fire place of any approved construction, which is provided with a casing 6, to which casing is attached a fastening element 7. In the passage way 8 of the chimney 9 there are placed a pair of supporting strips 10, the strips being positioned parallel with the side walls of the chimney. Each support terminates in an upper bent end 11 and a bent end portion 12. By referring to Figure 2 it will be observed that the bent ends 11 are embedded in the walls of

the chimney, while the bent end portions 12 engage a rectangular frame 13.

The construction of the frame 13 and its position within the throat of the chimney is best shown to advantage in Figure 3, and it will be noted that a pair of connecting rods 14 are journaled in the frame. Suitably attached to the rods 14 are a pair of arched plates 15 which are pivoted to the rods 14 and contact at their upper extremities. Each of the arched plates has provided adjacent its upper extremity a stud or eye bolt 16 and adjacent its lower extremity a stud or eye bolt 17. Suspended from the lower studs 17 is a cable 18 which supports a weight element 19. This weight element is positioned to lie directly beneath the contacting point of the arched plates 15, and by force of gravity will always be disposed in this position.

Connected to the upper studs or eye bolts 16 are two detachable cables 20 which have attached to their free ends a ring 21. This ring likewise connects with a cable 22 which extends within the chimney and is received by the fastening element 7 and is there locked in a fixed position. As shown to advantage in Figure 2, the apparatus is normally in the full line position, and upon disengaging the cable 22 from the fastening element 7, the apparatus will assume the dotted line position therein shown. To those skilled in the art it will be apparent that when the cable 22 is released from the fastening element 7, the weight 19 will tend to draw the lower extremities of the pivoted arch plates inwardly and will thus tend to separate the upper extremities from their normally contacting position and thus the passage way will be opened and heat will be allowed to travel therethrough.

In connection with the parts so far described, I intend to provide means whereby the interior of the chimney can be reached. To illustrate this feature I have shown means of access, shown as a whole by the numeral 23, which means can be built in the chimney. It will be noted, however, that this means of access is not absolutely necessary, for the supporting strips 10 can readily be made of a longer length of material than that shown and the flange elements can be made to fit in the sides of a chimney adjacent the top thereof. Thus the

whole apparatus can be lowered into that type of chimney where this operation is deemed advisable.

Attention is called to the fact that the 5 parts of this apparatus can be replaced if they are burned out or are injured and need replacement. In making the various parts a cheap class of material easily worked into shape and at the same time of a durable de- 10 sign, can be readily employed. When the apparatus is placed within the chimney there is nothing visible except the fastening element 7 and the ends of the cable, which elements can be made of an ornamental 15 character and thus add to the attractiveness of the attachment.

It is to be understood that the form of my 20 invention herewith shown and described, is to be taken as a preferred example of the same, and that various changes in the shape, size and arrangement of parts may be resorted to without departing from the spirit 25 of the invention or the scope of the subjoined claims.

Having thus described my invention, I 25 claim:

1. In combination with a chimney, a 30 damper comprising a frame, supporting strips having one end of each strip secured in the wall of said chimney and the opposite 35 end of each strip engaging said frame, plates pivotally connected with said frame, a weight element connected with and suspended from the lower extremities of said plates, and means connected with and adapted to cause said plates to be moved into and out of engagement with each other.

2. In combination with a chimney, a 40 damper comprising a rectangular frame, supporting strips having one end of each strip secured in the wall of said chimney and the opposite end embracing said frame, arched plates mounted within said frame and pivoted thereto, a weight element sus- 45 pended from said plates, a cable connected with and adapted to control the movement of said plates and extending downward

through the chimney to the front of the fire place, and means for receiving said cable to hold it in an adjusted position.

3. In combination with a chimney, a 50 damper comprising a rectangular frame, supporting strips, each of said strips terminating in a flanged portion at one end thereof and adapted to be fastened in the 55 wall of said chimney and terminating at the opposite end thereof in a bent portion and adapted to embrace said frame, arched contacting plates mounted within and pivoted to said frame, a cable connecting said plates 60 adjacent the lower extremities thereof and suspended therefrom, a weight element secured to said chain and positioned beneath the contacting point of said plates, and means connected with said plates adjacent 65 the upper extremities thereof and extending downward and outward through the chimney for controlling the movement of said plates.

4. In combination with a chimney includ- 70 ing a casing, a damper comprising a rec- tangular frame, supporting strips, each of 75 said strips terminating in a flanged portion at one end thereof and adapted to be fas- tered in the wall of said chimney and ter- 80 minating at the opposite end thereof in a bent portion and adapted to engage said frame, arched contacting plates mounted within and pivoted to said frame, a chain connecting said plates adjacent the lower 85 extremities thereof and suspended there- from, a weight element secured to said cable and positioned beneath the contacting point of said plates, means connected with said plates adjacent the upper extremities there- 90 of and extending downward and outward through the chimney for controlling the movement of said plates, and a fastening element secured to the fire place casing for receiving said chain to hold it in an adjusted position.

In testimony whereof I affix my signature.

JOHN M. GOODWIN.
